UNITED STATES PATENT OFFICE.

RICHARD S. CURRIE, OF TORONTO, ONTARIO, CANADA.

MEANS FOR MAKING TUBULAR ARTICLES.

Application filed April 19, 1924. Serial No. 707,705.

To all whom it may concern:

Be it known that I, RICHARD S. CURRIE, a subject of the King of Great Britain, and resident of the city of Toronto, county of York, Province of Ontario, in the Dominion of Canada, have invented certain new and useful Improvements in Means for Making Tubular Articles, as described in the following specification and illustrated in the accompanying drawings, that form part of the same.

The principal object of the invention is to reduce the cost of manufacture of bronze bushings by casting the metal in long lengths and a further object is to produce cast metal tubes of a uniform thickness, diameter and texture which may be used for bushings or for other purposes.

The principal feature of the invention consists in the application of a longitudinal stress to the core around which the metal is poured, whereby the expansion of the core is directed longitudinally and thereby restrained from lateral displacement.

The drawing is a sectional elevational view of a mould for carrying this invention into effect.

In the manufacture of bushings it has been the custom to cast the blanks in gated moulds and the blanks first have to be broken from the gate and rough trimmed on an emery wheel to remove the gate lug or fins, after which it is chucked and bored and then placed on an arbor and finished externally.

This process is very costly and it is proposed by the present invention to produce bushings by casting a tubular length of metal of fairly accurate dimensions which may be handled in a turret lathe, the inside and outside shaping and finishing being accomplished before the bushing length is cut off from the tube.

The principal difficulty in connection with producing bushings in this manner is to cast the metal in lengths sufficiently long to enable the minimum handling of the tube in a turret machine.

The desired result has been achieved by applying a longitudinal stress to the core while the metal is being poured.

In the accompanying drawing is shown a simple form of mould illustrating the application of the invention. The mould 1 is formed in two halves, one of which is

rigidly secured to the base 2 and the other is mounted on a hinged support 3 on the base. The interior of the mould is made the desired shape of the exterior of the tube to be cast, that is, it may be made cylindrical, hexagonal, or it may be made to form a casting with a plurality of collars or flanges.

A plate 4 is arranged to close the bottom of the mould and has a central opening 65 therein through which the core tube 5 is inserted. This core tube is provided with a flange 6 at the bottom end to engage the plate 4.

The tube 5 is formed with a plurality of 70 vent holes 7 and it is covered with a surface covering 8 of a suitable sand material which may be baked or otherwise hardened thereon.

The upper end of the core tube 5 has a 75 collar 9 secured thereto and this collar is shown supported by a laterally extending arm 10 secured to a vertically slidable member 11 and this slidale member is engaged by a compression spring 12 which applies 80 tension to the core tube, holding said tube centrally within the mould so that when the metal is poured therein it will not "float" but will remain in its proper axial position.

The pouring of the metal into the mould creates a very intense heat, first at the lower end of the mould with the result that an expansion takes place in the core tube at its lower end. If this expansion is allowed to take its normal course, the core tube will 85 simply increase in diameter as the metal is poured into the mould but by reason of the application of a longitudinal stress upon the core tube the said tube instead of expanding laterally will expand longitudinally and the core will remain practically of a uniform diameter throughout its length. The provision of a hollow core with vent holes allows the release of gases found in the pouring of the metal and a metal tube of 90 an extraordinary uniform texture is produced.

What I claim as my invention is:

1. A means for moulding tubular articles, comprising, a vertically arranged mould 105 formed in two longitudinal sections, one being rigid with the base and the other hinged to swing outwardly, a perforated core tube secured at the bottom end of said mould, and means carried by the fixed portion of 110

said mould and connected with the upper end of said core tube for applying an elastic tension thereto.

2. A means for moulding tubular articles, comprising a mould split longitudinally and having one-half thereof arranged on a hinged support, a plate closing the bottom

of the mould, a perforated core tube extending through said plate and flanged to engage the same, a sand covering on said core, and a spring connected to the top end of said core tube and exerting a longitudinal tension thereon.

RICHARD S. CURRIE.
